C. Mc Gregor,
Dressing Stares.

Patented July 2, 1836.

July 2-1836

33.

Capus, Mr. Gregory, of Newport, State of New Hampshire

Letter patent.

The subscriber, apprising to the Lally, Patent and making
part of his same, containing, a description in the words of the
late Lyons & Co. of Boston, himself, of his improvement, in the
mode of breaking or manufacturing stones for Roads, &c.,
and all such other stones as may then, present, shall come.

Lyons & Co. of Boston, in the County of Suffolk
and State of New Hampshire, are, seating—

To be known that I, the said Lyons & Co. of Boston, have
invented, contrived, made, and applied to use a new and even
further improvement in the mode of breaking or manufacturing
stones for Roads, &c., &c., and any other tasks, called the
water power. Name, design, specified in the words following (viz.)
This improvement consist in the application of per-
pendicular, & horizontal guides, & springs, & some horizontal guides as
more fully explained in the following described machine for breaking
or, dressing stones, &c., Two stones are fixed lengthwise on a horizontal
beam, parallel to each other, so far apart as to admit a stone of
the thickness, which appears, between their edges, and as long as
longer than the width of the stone which opening must be continuous
or cut so mortised, or through, the stone beam to let the stone
firmly grip, after it has passed between said stones, the beam
is to be firmly fixed to stand on foot at each end, or framed into
the building, above the machine as set up, of sufficient height
from the floor, for the stones to fall out, and be picked up, the
beam being of any convenient height, from six to ten feet more
or less, and the stones being of a power similar to the beam, from
one to two feet thick, and to be laid, placed, like the top of the airy
beam, so as to be supported by the beam, with horizontal guides
placed, so as to receive the stones, and to have a moving frame so made to
play—

play of an iron in a fine frame, similar to the frame of the saw, in a common saw mill, and may be put in motion by water, steam, horse, or any other power, in the same manner as the saw in a common saw mill, the upper part of the driving frame is made strong and firm so as to be of sufficient strength to drive the staves down between said knives through said beams, at each end of the frame there are fixed two upper cross said horizontal beams, and at each end of said frame about half a foot square or more, so made or kept and so fit that two fine pointed cross bars, on the top of them two other are fixed, lengthwise of said beam, parallel with each other and far enough apart to admit the two horizontal guides hereafter described to lie side by side between them and also about the same depth between them with said driving beams centered between said upper cross bars, and the two horizontal guides from them to lie inches in diameter across or less, and generally as long as the said horizontal beams, are placed over the horizontal beams said upper cross bars, laying on said lower cross bars and supported by them and goes on the posts at the end or by other cross bars so that they may project out upon the springs by the side where the machine is in operation, there are four springs of wood, steel, iron or other elastic material of sufficient strength two on each side of said horizontal beam a little way from the ends of said horizontal guides, to keep them from passing out too far and to make them project upon said guides the same when it is done these guides are best to be round but may be of other figures or shapes, —

The two perpendicular guides are fixed & fastened to the two aforesaid upper cross bars, one on each side of the two knives for driving the staves which are parallel and perpendicular with an opening between them in which the frame the staves which it is intended to drive, the two perpendicular guides must pass upon the top of the frame frame and through a space of other opening which makes of them so that within the machine

is an iron bar and lay along the top, the bottom of each guides
consisting of four slates two upper and base -
called as by a model deposited in the Patent Office of the United
States drawing of which is herewith annexed in which Fig. 1 repre-
sents the frame, Fig. 2, the driving frame Fig. 3, the horizon-
tal beam which passes through the driving frame - and posts to it,
Fig. 4, representing the staffing or covering of the beam below
the frame each corner of which is chamfered off that while the
stave is driven through the beam the shoring & splinter may
fly off at the out side - Fig. 5 represents under edge bar,
Fig. 6, represents upper edge bar, Fig. 7, represents horizontal
guide, Fig. 8, springs to horizontal guide three turned other end
being in shade of frame are not here represented Fig. 9, the upright
guides, Fig. 10, the upper part of driving frame is held in place
and steady upright guides - This improvement can
not in the construction and application of the horizontal guides &
springs to them, and of the said upright guides (knives having
been hitherto fixed in a frame for dressing staves) to guide, keep
in place, steady the staves and them from breaking when driven
In witness whereof the foregoing is a true specification
of my said improvement as above described I have caused set
my hand this fourteenth day of December A.D. 1833 -
